UNITED STATES PATENT OFFICE

JESSE G. KING, OF DAYTON, OHIO, ASSIGNOR, BY MESNE ASSIGNMENTS, TO FRIGID-AIRE CORPORATION, A CORPORATION OF DELAWARE

REFRIGERATING APPARATUS

Application filed November 27, 1928, Serial No. 71,515.

This invention relates to cooling units for mechanical refrigerators. An object of the present invention is to provide a cooling unit comprising a main or central upright section so constructed as to provide an effective heat-transfer relationship between the refrigerating medium contained therein and the air of the refrigerator or such other medium which is to be cooled, and heat transfer means extending laterally from said main section to provide suitable supports or compartments for the reception of ice trays or the like. In the preferred embodiment of the present invention the main section referred to is so constructed or fashioned as to also provide a compartment or support for ice trays.

Further objects and advantages of the present invention will be apparent from the following description, reference being had to the accompanying drawings, wherein a preferred form of the present invention is clearly shown.

In the drawings:

Fig. 1 shows a cooling unit built according to this invention, installed in a conventional type of ice box having a relatively shallow ice chamber in the top thereof.

Fig. 2 shows a front elevation of the cooling unit on a larger scale, but with the ice drawers removed from their compartments.

Fig. 3 is a side elevation of the cooling unit of Fig. 2.

Like reference characters refer to like parts throughout the several views.

Referring to the drawings, 10 designates a conventional type of ice box or refrigerator cabinet having a lower food chamber 11 and an upper ice chamber 12 extending across the top of the box. When ice is used in such a box, it rests upon an ice grid placed upon the floor 13 of the chamber 12. The warmer air from the food chamber 11 rises through the two side flues 14, circulates around the ice and then passes down through the central opening 15 in the floor 13, thus maintaining a proper air circulation between the food and ice chambers. 16 is a drip duct for leading off the water from the melting ice as well as the water of condensation from chamber 12.

Now, this invention provides a cooling unit

which may be placed within the chamber 12 and connected by suitable supply and return-refrigerant ducts to the compressor unit which may be located in the basement or any other suitable place outside the box 10. This cooling unit comprises an elongated header or tank 20, which serves as a reservoir for liquid refrigerant. A suitable float valve mechanism is provided within tank 20 to maintain the liquid refrigerant at a substantially constant level, the liquid being led into tank 20 through duct 21 and the vapor being returned to the compressor unit through return duct 22. The structure so far described, is well known in the art as exemplified by British Patent No. 200,539 of 1923, to John R. Reogle.

A series of cooling ducts in the form of loops 25 and 26 are connected preferably in parallel relation to the header 20 at a point below the liquid level therein. All the loops 25, 26 are preferably of substantially identical shapes, but alternate loops are reversed when they are connected to the header 20, thereby giving the structure clearly shown in Fig. 2. Each loop comprises a vertical leg or portion 30 extending downwardly from header 20, a laterally extending portion 30^a, an upwardly extending portion 31, and a laterally extending portion 31^a inclined upwardly at its inner end and joined with the header 20. The part of the cooling unit immediately below the header 20, bounded by the vertical legs 30, and the intermediate portions of the horizontal leg 30^a constitutes the central or main vertical section thereof, and, as here shown, it may be hollowed out or fashioned so as to provide a compartment or enclosure 27 therein for the reception of one or more metallic sleeves 32 to receive ice-freezing pans or trays 33. The parts of the cooling unit extending laterally of the said main section form rearwardly extending compartments or enclosures 28 and 29 on opposite sides of the compartment 27. These parts, which are in the form of supports or loops support metallic sleeves, shown at 35, which are adapted to receive elongated ice-freezing trays 36. Preferably, the tubes from which loops 25 and 26 are made are

flattened throughout except at the ends 24 where the loops are connected to the header 20. Such flattening provides a greater cooling surface per unit volume of liquid refrigerant contained in the loops, and also provides a greater space between the loops and, hence, reduces the tendency of the frost which forms on the exterior of the loops to bridge across the gap between the loops and thereby reduce the effective cooling surface of the unit. Preferably each of the compartments or enclosures contains one or more housings or sleeves for the pans, made of metal of good thermal conductivity, which act as supports for the pans, covers to keep moisture from dripping into them during defrosting, and thermal conductors to transfer heat to the loops. As shown in Fig. 2, two of such sleeves 32 are placed in the enclosure 27 and one sleeve 35 is placed in each of the enclosures 28 and 29. The sleeves may be secured to the tubes in any suitable manner, as by soldering, to form a thermally conducting joint. The ice pans 33 are placed in sleeves 32 in the inner freezing enclosure, while the pans 36 are placed in the sleeves 35 in the outer freezing enclosures. The lower and upper horizontal legs 30^a and 31^a of the laterally extending loops 31 lie parallel to the sleeves 35 and as close thereto as the corners 31^b of the tubes will permit. Each sleeve is provided with elevated supports 34 for the pans 33, 36. The compact arrangement of the sleeves 32 beneath the header, between the sleeves 35 and between the vertical tubes 30 of the main section of the cooling unit affords protection from air currents circulating over the cooling unit, while the sleeves 35 and laterally extending loops 31 are exposed to the currents.

In the operation of this cooling unit, since the laterally-projecting portions 31 of the cooling loops 25 and 26 will be more exposed to the warm air rising through the flues 14 and passing back down through the central opening 15 than the inside legs 30 of the cooling loops, ice will freeze more slowly in the two side enclosures 28 and 29 than it will in the central enclosure 27. This is readily apparent, since the central section or enclosure being nested between the side enclosures or zones, is protected thereby. The side enclosures, which overlap the central section shield the latter from circulating air passing over the cooling unit and such air that comes in contact with the section will be precooled when passing between legs or portions 31^a of the side enclosures or compartments. The central enclosure may then be used for freezing ice at a conveniently rapid rate when ice is wanted in a hurry, and the two side enclosures used for freezing ice slowly when there is no necessity for rapid freezing, or for storage of the already frozen ice trays. An important advantage of this

construction lies in the fact that the laterally-projecting portions 31 are so exposed to the circulating air that frost will form on their exterior surfaces at a much slower rate and, hence, there is a much more efficient heat transfer between the air and cooling loops; and this occurs while the central ice trays 33 are maintained at such a temperature that ice will be frozen therein at a conveniently rapid rate. In the intermittent operation of the compressor unit which draws off the vaporized refrigerant from the cooling unit through duct 22, the temperature of the cooling unit will vary between a maximum and a minimum. In the structure of this invention, any frosting which occurs on the laterally-projecting portions 31 of the cooling loops during the minimum temperature period will ordinarily disappear during the maximum temperature period and, thus, maintain these portions 31 free from excessive caking up with frost.

While the form of embodiment of the invention as herein disclosed, constitutes a preferred form, it is to be understood that other forms might be adopted, all coming within the scope of the claims which follow.

What is claimed is as follows:

1. A cooling unit for mechanical refrigerators comprising, in combination, an elongated header serving as a reservoir for liquid refrigerant, a series of duct loops depending from said header and connected thereto in parallel relation along the length of said header, said loops being arranged to provide three laterally-spaced freezing compartments adapted to receive ice trays, all of said loops surrounding the center freezing compartment and alternate loops surrounding each of the two side freezing compartments, whereby said center freezing compartment will freeze ice quicker than the two side compartments.

2. A cooling unit for mechanical refrigerators comprising, in combination, an elongated header serving as a reservoir for liquid refrigerant, a series of duct loops depending from said header and connected thereto, in parallel relation along the length of said header, said loops being arranged to form three laterally-spaced freezing compartments adapted to receive ice trays, the center freezing compartment containing two ice trays while the side compartments each contain a single ice tray, all of said loops surrounding the center compartment while alternate loops surround each side compartment.

3. A cooling unit for mechanical refrigerators comprising, in combination, a header serving as a reservoir for liquid refrigerant, a series of duct loops connected with said header to form three laterally-spaced compartments for ice-making receptacles, all of said loops surrounding the center compartment and each alternate loop surrounding one of the side compartments, whereby said center

compartment will freeze ice quicker than the side compartments.

4. A cooling unit for mechanical refrigerators comprising, in combination, a header serving as a reservoir for liquid refrigerant, a series of duct loops connected with said header to form a plurality of compartments for ice-making receptacles, all of said loops surrounding one of said compartments and 10 certain of said loops surrounding each of the other compartments.

5. A cooling unit for mechanical refrigerators comprising, in combination, a header serving as a reservoir for liquid refrigerant, a series of duct loops connected with said header, the loops projecting laterally on opposite sides of said header and forming ice-making compartments disposed laterally with respect to one another, said loops including 20 portions disposed parallel and adjacent one of said compartments.

6. A cooling unit for mechanical refrigerators comprising, in combination, a header serving as a reservoir for liquid refrigerant, a series of duct loops connected with said header, the loops projecting laterally on opposite sides of said header and arranged to 25 form ice-making compartments disposed laterally with respect to one another, said loops including horizontal portions disposed above and adjacent one of said compartments.

7. A cooling unit for mechanical refrigerators comprising in combination a header adapted to contain a refrigerant, a plurality 35 of refrigerant ducts extending from the header to form freezing compartments for ice-making receptacles, a plurality of supports for ice-making receptacles within the compartments, portions of said ducts extending between and in intimate metallic relation 40 with said supports.

8. A cooling unit for mechanical refrigerators comprising in combination a header adapted to contain refrigerant, a plurality of refrigerant ducts connected with the header and disposed in a vertical plane and forming freezing compartments for ice-making receptacles, and a plurality of supports for ice-making receptacles disposed side by side 50 within the compartments, portions of the ducts being disposed in a vertical plane between said supports.

9. A cooling unit for a mechanical refrigerator comprising in combination a reservoir adapted to contain refrigerant, a central heat transfer section extending downwardly from said reservoir, said central section including refrigerant duct means connected with said reservoir and extending 55 rearwardly a substantial distance, and refrigerant duct means extending rearwardly a substantial distance and also extending laterally from said central section to provide a support on either side of said central section 60 for receiving elongated ice trays.

10. A cooling unit for a mechanical refrigerator comprising in combination a reservoir adapted to contain refrigerant, a central heat transfer section extending downwardly from said header, said central section including refrigerant duct means connected with said reservoir and extending rearwardly a substantial distance, and refrigerant duct means extending rearwardly a substantial distance and also in intimate metallic contact 75 with said section and extending laterally therefrom to provide a support for an elongated ice tray.

11. A cooling unit for a mechanical refrigerator comprising in combination a reservoir adapted to receive refrigerant, a hollow heat transfer section adapted to receive therein an ice tray and having a refrigerant passage 80 connected with said reservoir, and metallic heat transfer means extending laterally from said section to provide a support for an ice tray.

12. A cooling unit for mechanical refrigerators comprising in combination, a header and heat exchange means associated with the header, said heat exchange means including a portion for providing a main freezing section below the header and arranged to receive an ice-making receptacle, and including another portion providing a freezing zone arranged to receive an ice-making receptacle and disposed laterally to the main section and in intimate thermal relation to the circulating medium cooled thereby while shielding the main freezing section from such circulating medium.

13. A cooling unit for mechanical refrigerators comprising in combination, a header and heat exchange means associated with the header, said heat exchange means including a portion for providing a main freezing section below the header and arranged to receive an ice-making receptacle, and including other portions providing freezing zones arranged to receive ice-making receptacles and disposed laterally on opposite sides of the main freezing section in intimate thermal relation to the circulating medium cooled thereby while shielding the main freezing section from such circulating medium.

14. A cooling unit for mechanical refrigerators, comprising in combination, conduit means for circulating a refrigerating medium, said means including a portion providing three laterally disposed freezing compartments each adapted to receive an ice-making receptacle, the outside compartments being in intimate thermal relation with the circulating medium cooled thereby while shielding the central compartment from such circulating medium.

15. A cooling unit for mechanical refrigerators, comprising in combination, a series of duct loops arranged to provide three laterally disposed freezing compartments adapt-

- ed to receive ice-making receptacles, said loops being of non-symmetrical contour and arranged in staggered relation with the loops offset laterally with respect to one another, 5 certain portions of the loops providing the dividing walls between said compartments.
16. A cooling unit for a mechanical refrigerator comprising, in combination, a header serving as a reservoir for refrigerant, a plurality of ducts connected with the header, said ducts having portions projecting laterally on opposite sides of said header and cooperating to form rearwardly extending ice-making compartments disposed laterally with respect to one another.
17. A cooling unit for a mechanical refrigerator comprising, in combination, a header serving as a reservoir for refrigerant, a plurality of ducts connected with the header, 20 said ducts having non-symmetrical shapes and alternate ducts being reversely turned and cooperating to form ice-making compartments disposed laterally with respect to one another.
18. A cooling unit for a mechanical refrigerator comprising, in combination, a header serving as a reservoir for refrigerant, a plurality of ducts connected with the reservoir, 25 said ducts being arranged in a plurality of sets, one set of said ducts overlying and having a portion extending beyond another set, said extending portion cooperating with the second set of ducts to form a plurality of ice-making compartments, one of said ice-making compartments being within said extended portion.
19. A cooling unit for a mechanical refrigerator comprising, in combination, a header serving as a reservoir for refrigerant, a plurality of ducts connected with the reservoir, 40 said ducts being arranged in a plurality of sets, one set of said ducts overlying another set and cooperating therewith to form a plurality of ice-making compartments disposed laterally with respect to one another, one of 45 said ice-making compartments extending laterally beyond said second set of ducts.
20. A cooling unit for a mechanical refrigerator comprising, in combination, a header 50 for refrigerant, a plurality of ducts connected with the header, said ducts being arranged in sets, certain of said sets projecting laterally to one side of the header and said sets cooperating to form a plurality of ice-making compartments disposed laterally with respect to one another, one of said ice-making compartments extending laterally beyond 55 said second set of ducts.
21. A cooling unit for a mechanical refrigerator comprising supports elongated rearwardly for receiving elongated ice trays thereon, a central upright heat transfer section in intimate thermal contact with a refrigerant, said supports and said upright heat transfer section being disposed laterally with 60 respect to one another and said section extended rearwardly and substantially coextensive with the length of said supports and thermally connected therewith.
22. A cooling unit for mechanical refrigerators comprising a main upright heat transfer section hollowed out to receive a refrigerant therein, an ice tray support elongated rearwardly for receiving thereon an elongated ice tray, said support overhanging said main upright section and supported from one side thereof and said main upright section extending rearwardly to substantially the depth of said elongated support and being connected thereto alongside thereof.
23. A cooling unit for mechanical refrigerators comprising a refrigerant reservoir, refrigerant conduit means connected with said reservoir, a portion of said means extending more remote from the header than certain other portions, said portion cooperating to provide a plurality of horizontally elongated compartments for ice trays, said compartments lying adjacent and alongside of one another.
24. A cooling unit for mechanical refrigerators comprising a reservoir for refrigerant, heat exchange means thermally connected with the reservoir and including a portion providing a central ice-making compartment, and having other portions extending beyond the first portion for providing other ice-making compartments alongside of said central ice-making compartment.
25. Refrigerating apparatus comprising, 100 in combination, a refrigerator cabinet having insulated side walls, means providing access to said cabinet from the front, a cooling unit within said cabinet, said cooling unit comprising a main upright heat transfer section extending from front to rear and disposed substantially midway between the insulated side walls of said cabinet, and heat transfer means carried by said main upright heat transfer section and extending laterally from one side thereof towards one of the side walls of said cabinet to provide a support for an ice tray.
26. Refrigerating apparatus comprising, 105 in combination, a refrigerator cabinet having insulated side walls, means providing access to said cabinet from the front, a cooling unit within said cabinet, said cooling unit comprising a main upright heat transfer section extending from front to rear and disposed substantially midway between the insulated side walls of said cabinet, and means extending from opposite sides of said main upright section towards the side walls of said cabinet to provide a freezing compartment on either side suitable for the reception of an 110 ice tray therein.
27. A cooling unit for mechanical refrigerators comprising three laterally-spaced supports for ice-making receptacles, a refrigerant reservoir, heat exchange means includ- 115
- 120
- 125
- 130

ing conduit means connected with the reservoir and providing a freezing zone for said supports, said heat exchange means including portions extending between said supports, 5 providing compartments for said supports, certain of said compartments being disposed on opposite sides of the reservoir.
